POULTRY COOP.

APPLICATION FILED SEPT. 6, 1916.

Patented Jan. 8, 1918.

2 SHEETS—SHEET 2.

UNITED STATES PATENT OFFICE.

GEORGE A. MCGAHAN, OF CINCINNATI, OHIO, ASSIGNOR OF ONE-FIFTH TO WM. M. CATRON AND ONE-FIFTH TO C. I. ROSS AND J. S. COOPER, ALL OF SOMERSET, KENTUCKY.

POULTRY-COOOP.

1,253,067.

Specification of Letters Patent.

Patented Jan. 8, 1918.

Application filed September 6, 1916. Serial No 118,682.

To all whom it may concern:

Be it known that I, GEORGE A. MCGAHAN, a citizen of the United States, residing at Cincinnati, in the county of Hamilton and State of Ohio, have invented certain new and useful Improvements in Poultry-Coops; and I do hereby declare the following to be a full, clear, and exact description of the invention, such as will enable others skilled 10 in the art to which it appertains to make and use the same.

The object of this invention is to provide a portable coop for poultry, which can be cheaply manufactured and will be of strong 15 and durable construction so as to admit of a plurality of coops being arranged in superposed positions during shipment.

Other objects will appear and be better understood from that embodiment of my invention of which the following is a specification, reference being had to the accompanying drawings forming a part thereof, in which:

Figure 1 is a perspective view of the frame 25 of the coop,

Fig. 2 is a top plan view of the coop,

Fig. 3 is a side elevation of the coop with the lower end thereof in section, and

Fig. 4 is a detail sectional view, showing 30 the construction of the meeting ends of the lower rails of the frame.

Referring to the drawings in detail, the coop is shown as consisting of a frame structure formed of upper and lower side rails 1 and 2, upper and lower end rails 3 and 4 and corner posts 5, which are interposed between the upper and lower rails. The rails 1, 2, 3 and 4 are of angular shape in cross section and each of the side rails 1 and 2 35 has its opposite ends provided with extensions 6. The lower end rails 4 have the upper surfaces thereof cutaway, adjacent the opposite ends of the rails, to provide extensions 7, which engage beneath the extensions 40 6 of the lower side rails 2, as shown in Fig. 1, so as to admit of the lower surfaces of the lower side and end rails 2 and 4 lying flush. The end rails 3 have their lower surfaces 45 cutaway at opposite ends of the rails to provide extensions 8, which engage over the extensions carried by the adjacent ends of the upper side rails 1 so as to admit of the 50 surfaces of the rails 1 and 3 lying flush.

The corner posts 5 have their lower ends

resting upon the upper sides of the extensions 6, carried by the lower side rails 2, and their upper ends engaging under the extensions carried by the upper side rails 1. Fastening elements 9 extend through the extensions on the upper and lower rails and into 55 the post so as to secure the rails to the post.

A brace 10 extends longitudinally of the lower side of the frame and is formed of a single length of wire bent and extended through openings 11 in one lowermost end 60 rail, as shown in Fig. 1, and has the strands thereof twisted, at a point centrally of the frame, to provide a substantially diamond shaped loop 12, the ends of the strands being then continued in diverging relation and 65 passed through openings in the opposite lower end rail 4 and terminally upset against the outer side of the end rail, as shown in dotted lines in Fig. 1.

Encircling the upper and lower rails 1 75 and 2 are brace wires 14. These brace wires are secured to the rails by means of fastening elements 15 and each of the brace wires has its opposite ends overlapping, as shown in Fig. 3, and electrically welded together. 80 Brace wires 16 also encircle the posts 5 and have their opposite ends overlapping and electrically welded, as shown in Fig. 3.

Vertical wires 17 are positioned on the sides and ends of the frame and intersect the 85 wires 16 and are electrically welded to the wires 16 at the points of intersection. Longitudinally extending wires 18 extend along the upper side of the upper rails 1 and have connection with the rails by means of fastening elements 19, a second pair of longitudinally extending wires, designated 20, 90 extend across the top of the frame and have their opposite ends secured to the upper end rails 3 by means of fastening elements 21. 95 Extending transversely of the top of the frame are a plurality of wires 22, which intersect the wires 18 and 20, and are electrically welded to the wires 18 and 20 at the 100 points of intersection.

Certain of the wires 22 are divided at a point between the wires 20 to provide an entrance opening 23, which is normally closed by means of a door formed by a pair of spaced wires 24 which extend parallel with 105 the wires 20, and a pair of transverse wires 25, which extend across the wires 24 and are electrically welded thereto. Each of the

wires 24 has one end looped around a rod 26, which extends transversely of the frame, and the opposite ends of the wires 24 extend beneath one of the transverse wires 22, when the door is closed, so as to prevent accidental opening of the door. When it is desired to open the door, the wires 24 are flexed so as to admit of the free ends of the wires being drawn from beneath the adjacent transverse rods 22 so as to admit of the door being opened.

The coop is provided with a bottom wall 27, which rests upon the horizontal flanges of the lower side and end rails 2 and 4, and is secured thereto in any suitable manner. It will be noted that by virtue of so mounting the lower wall or floor 27 the same will be held above the ground or other supporting surface so as to keep the floor in a dry condition. The brace 10 will prevent collapse of the bottom wall 27 when a relatively heavy load is placed thereon, and said brace will also assist in retaining the lower side and end bars in frame formation. The loop 12 lies in engagement with the under side of the bottom wall 27, and by virtue of this engagement the strands of the wire of which the brace is formed will be prevented from becoming untwisted.

By virtue of employing the brace wires 14 and 16 and electrically welding the same to the wires 17, it will be seen that the strength of the coops will be maximized so as to admit of a large number of coops being ar-

ranged in superposed position during shipment.

What I claim is:

1. A coop of the class described including a frame having upper and lower side rails and upper and lower end rails, extensions 49 formed on the terminals of the side rails and lying between the upper and lower surfaces of said side rails, extensions formed on the terminals of the end rails, the extensions on the uppermost end rail overlying the extensions on the upper side bars, and the extensions on the lower end rails underlying the extensions on the lower side rails, corner posts interposed between the extensions on the upper and lower side rails, and bracing elements 45 interposed between and connected to the lower end rails.

2. A coop including a floor supporting frame having end rails provided with openings, a floor resting on the frame, a brace 55 disposed below the floor and formed of a single length of wire bent upon itself and having the strands thereof extending through the openings in the end rails, the said strands being twisted about each other to provide a loop disposed centrally of and engaging the under side of the floor.

In testimony whereof I affix my signature in presence of two witnesses.

GEORGE A. McGAHAN.

Witnesses:

B. C. DARTAN,
LUCILLE HAIL.
